LOCOMOTIVE CYLINDER AND CYLINDER
SADDLE CONSTRUCTION

James G. Blunt, Schenectady, N. Y.

Application November 18, 1933, Serial No. 698,575

14 Claims. (Cl. 105—44)

This invention relates to cylinder and cylinder saddle constructions of locomotives.

An object of the invention is to provide an improved working cylinder and cylinder saddle construction for a locomotive embodying box-shaped reinforcing portions arranged to afford an increased amount of strength and to offer an added amount of resistance to stresses imposed upon the construction under operating conditions.

10 A further object is to provide a construction of the character described which will comprise a casting wherein reinforcing portions are arranged to afford increased strength at the particular locations which are subjected to great strains and stresses and to present box section portions surrounding cored wall openings to prevent initial and progressive fractures.

20 Other and further objects of and advantages achieved by the invention will be apparent from the following detailed description and claims.

In the accompanying drawings, Figure 1, at the right, is a front end view of a cylinder, valve chest and half cylinder saddle construction embodying the present invention, and at the left, is a vertical sectional view taken on the line I—I of Fig. 2, of an adjoining similar cylinder, valve chest and half cylinder saddle construction; Fig. 2, at the right, is a plan view of the construction shown at the right of Fig. 1, and at the left, is a horizontal sectional view taken on the line II—II of Fig. 1; Fig. 3 is a section taken on the line III—III of Fig. 1; Fig. 4, at the right, is a section taken on the line IV—IV of Fig. 1, of the rear half, and at the left, a side view of the front half, of the construction shown at the left of Fig. 1; and Fig. 5, at the right, is a bottom view of the construction shown at the right of Fig. 1, and at the left, is a section taken on the line V—V of Fig. 1.

In common locomotive practice two working cylinders are employed, disposed at the outer sides of the locomotive side frame members, although in some locomotives a third working cylinder is disposed midway between the side frame members. It is a common practice where two working cylinders are employed to form each working cylinder, its distribution valve chest and a half cylinder saddle portion as a one piece casting and to use two of such castings, one of which is a duplicate of the other, attached to each other. This procedure is followed in the exemplification of this invention herein described for the purpose of illustration, as will presently be apparent.

These constructions or castings are subjected in service to many and various strains and stresses,

and it is essential that they possess sufficient strength to withstand them with an ample margin of safety. The cylinder saddle portions serve as a frame cross brace and as a boiler support, and while they must necessarily have sufficient strength for these purposes, they must also have sufficient strength to resist piston thrusts of the opposite working cylinders simultaneously suddenly applied in opposite directions. Furthermore, in such constructions many and various 10 stresses and strains are occasioned by the different temperatures to which the different parts thereof are subjected, as for instance the relatively high temperature to which the tops of the cylinder saddle portions are subjected due to the 15 smoke box adjacent thereto, the relatively high temperatures to which the valve chests, steam passages and working cylinders are subjected due to the steam therein, and the relatively low atmospheric temperatures to which the outer sides 20 of the constructions are subjected due to the atmosphere, and are occasioned by the sudden changes of temperature, as for instance those caused by the sudden shutting off of steam. Further, such constructions are usually mounted 25 above a center plate of a four-wheel leading truck, or an equalizing lever fulcrum of a two-wheel leading truck, and the resistance of the engine truck centering device resolves itself into an upward thrust against the under sides of the 30 constructions. These constructions are also subjected to various other stresses and strains including the shocks of coupling and sudden brake applications, stresses due to centrifugal forces imposed while entering and passing through 35 curves, cross-overs and irregular track, as well as stresses and strains resulting from heat distortions in the smoke box which is attached to the tops of the cylinder saddle portions, from 40 firing up and cooling down the boiler.

Practice has shown that there are certain locations in such constructions as aforementioned which are especially subjected to the aforementioned stresses and strains and which might be termed critical points or locations. It is especially desirable therefore that the constructions be reinforced at these critical locations and the present invention provides novel means affording such reinforcements. More particularly it provides at these critical locations substantially box 50 section formations giving relatively great strength and increased resistance to stresses and strains where most needed, without excessively increasing the weight of the constructions.

While the approved embodiment or exemplifi- 55

cation of the invention illustrated in the accompanying drawings, and hereinafter described, is in connection with the commonly used form of cylinder, valve chest and cylinder saddle of the 5 so called half saddle type construction, it will be understood that the invention may also be applied in connection with various differently formed constructions, such as where two or more working cylinders are integrally cast with a saddle 10 in a one piece construction.

Referring in detail to the drawings, a pair of power cylinders, valve chests therefor, and a cylinder saddle therefor are provided by two separate integrally cast constructions indicated generally by the numerals 1 and 2. One of these constructions is a duplicate of the other, and for the purpose of brevity only the construction 1 shown at the left of Fig. 1 will be described in detail. The parts of the construction 2 are indicated in 15 the figures by reference designations identical to those of the corresponding parts of the construction 1 and the several views of the construction 2 may be referred to as illustrative of both of the constructions.

25 The construction 1 comprises a working cylinder 3, a valve chest 4 and a cylinder saddle portion 5. A passageway 6 is provided for the introduction of live steam directly to the valve chest. A distribution valve (not shown) is provided for 30 the valve chest in the usual manner and inlet steam passageways 7 and exhaust stem passageways 8 are provided, the passageways 8 extending through the cylinder saddle portion 5 and terminating at the top thereof.

35 The cylinder saddle portion 5 comprises a top wall 9, front and rear end walls 10 and 11 respectively, an inner side wall 12, an outer side wall 13 and a bottom wall 14 which extends from the side wall 12 toward the working cylinder 3, and is 40 cut away to provide an opening 14a. The outer side wall 13 is curved at its lower portion and extends substantially horizontal to the valve chest with which it merges. The top wall is extended beyond the end walls 10 and 11 and outer side 45 wall 13, providing bolting flange portions 15 for bolting the cylinder saddle portion to the smoke box. A longitudinal vertical wall 16 extends downwardly from the bottom wall 14, providing means for attachment to a locomotive side frame 50 member. All of the aforescribed parts are of the usual design and construction.

While in the embodiment illustrated a valve chest is shown as an integral part of the construction, it will be understood that any particular 55 valve chest construction is not essential, and that the invention is applicable to constructions embodying as an integral structure only a cylinder and cylinder saddle portion, or cylinders and a cylinder saddle, as for instance in arrangements 60 where slide valves are employed and separate valve chests are secured on the cylinders. In such an arrangement the wall 13 would of course be extended down to the valve seat which would be an integral part of the cylinder in the usual manner. Further while the embodiment illustrated is for a steam locomotive it will be understood that where cylinders and cylinder saddles 65 are used in connection with air operated locomotives the invention would also be applicable.

70 The following described structure embodies the improvement of the present invention. At the juncture of the top wall 9 and the outer side wall 13, the construction is formed to provide a box-shaped portion defining a cored longitudinally extending horizontal space 18. A vertical wall 19

spaced from and parallel to the wall 13 extends downwardly from the wall 9 and a horizontal wall 20 spaced from the wall 9 extends inwardly from the wall 13 to the bottom edge of the wall 19. Thus the walls 19 and 20 and the opposite portions of the walls 13 and 9 respectively form the box-shaped portion defining the cored space 18 which extends substantially the length of the cylinder saddle portion. 5

At the juncture of the inner side wall 12 and the bottom wall 14 the construction is formed to provide a box-shaped portion defining a cored longitudinally extending horizontal space 21. A vertical wall 22 spaced from and parallel to the side wall 12 extends upwardly from the bottom wall 14 and a horizontal wall 23 spaced from and parallel to the wall 14 extends outwardly from the side wall 12 to the top edge of the wall 22. Thus the walls 22 and 23 and the opposite portions of the walls 12 and 14 respectively form the box-shaped portion defining the cored space 21 which extends substantially the length of the cylinder saddle portion.

The construction is also formed to provide a box-shaped portion defining a cored vertical space 25 24 at the juncture of the wall 11 and the wall 13, which space extends substantially the height of the cylinder saddle portion. A wall 25, spaced from and parallel to the wall 11, extends downwardly from an end of the wall 20, the connection between the walls 25 and 20 being curved, and vertical spaced parallel inner and outer walls 26 and 27 respectively connect at their forward edges with the respective adjacent vertical edges of the wall 25 and at their rear edges with the 35 wall 11. The upper end of the wall 27 connects with a portion of the wall 13 which is opposite and parallel to the wall 26, the upper end of the wall 26 merges with the wall 19, and the upper portion of the outer edge of the wall 25 40 connects with the wall 13. Thus the walls 25, 26 and 27, the portion of the wall 13 opposite the wall 26, and the portion of the wall 11 opposite the wall 25 form the box-shaped portion defining the cored space 24. 45

Similarly to and opposite to the space 24 a box-shaped portion is provided defining a cored space 28 at the inner side of the front end wall 10, having walls 29, 30 and 31, corresponding to the walls 25, 26 and 27 respectively and portions of 50 the walls 13 and 10. The cored spaces 24 and 28 merge at their upper ends with the cored space 18. The lower ends of the walls 26 and 30 are curved and extend inwardly and substantially horizontally to and merge with the wall 23. 55

A vertical wall 32 extends longitudinally between the walls 25 and 29 a short distance upwardly from the bottom wall 14 to the lower ends of the walls 25 and 29. A substantially horizontal wall 33 extends from the upper edge of the 60 wall 32 outwardly. The middle portion of the wall 33 is provided with an outward extension 33a which connects with the cylinder 3 and is downwardly curved for this purpose at its outer end. Transversely extending walls 34 and 35 extend 65 downwardly from the opposite edges of the extension 33a. The lower portions of the walls 34 and 35 connect the cylinder 3 with the wall 16. The lower ends of the walls 34 and 35 converge and are connected at their lower edges. Thus between 70 the cylinder 3 and the wall 16 at the central portion of the cylinder saddle, the walls 34 and 35 and the extension 33a provide a box-shaped portion defining a transversely extending cored space 36. The cored space 36 is closed at its outer end 75

by the cylinder 3, at the lower part of its inner end by the wall 16 and at the upper part of its inner end by the wall 32.

Longitudinally extending walls 37 and 38 extend toward the rear and front end walls 11 and 10 respectively from the inner ends of the walls 34 and 35. It will be apparent that inwardly from the wall 37 a box-shaped portion defining a cored space 36a is provided by the wall 37, the rear end portions of the walls 32 and 33, and an outer rear portion of the wall 14. Also inwardly from the wall 38 a box-shaped portion defining a cored space 36b (similar to the cored space 36a) is provided by the wall 38, the forward end portions of the walls 32 and 33 and an outer front portion of the wall 14. The cored spaces 36, 36a and 36b merge with each other at their adjacent ends.

A vertical wall 39, spaced from and parallel to the wall 11, extends from the wall 32 to the wall 22, and a similarly spaced wall 39a extends from the wall 37 to the cylinder 3. The bottom of the wall 25 merges with the wall 39 and connects with the rear ends of the walls 32 and 33. A horizontal wall 40 extends from the upper edge of the wall 39 to the wall 11 and extends transversely of the construction inwardly from the lower end of the wall 26 and merges with the wall 23. There is thus provided by the walls 39 and 40, an inner rear portion of the wall 14 and a lower inner portion of the wall 11, a box-shaped portion defining a cored space 40a merging at its outer end with the cored space 24 and at its inner end with the cored space 21. A substantially horizontal wall 41 connects the upper edge of the wall 39a with the wall 11, the wall 41 extending transversely of the construction from the lower end of the wall 27 to a location near the middle of and slightly above the cylinder 3. The walls 39a and 41 extend downwardly as far as the lower edge of the wall 16, and extend, transversely of the cylinder saddle portion, between the wall 16 and the cylinder 3. The wall 39a slants rearwardly at its lower portion and merges at its lower end with the wall 11. Thus the walls 39a and 41 and a lower portion of the wall 11 provide a box-shaped portion defining a cored space 41a, which space is open to the atmosphere at its outer end immediately above the cylinder 3 and merges with the cored spaces 24 and 36a. The inner forward end portion of the wall 41 connects with the wall 33.

At the forward end of the construction a wall 42 spaced from and parallel to the wall 10 extends from the wall 32 to the wall 22 and a similarly spaced wall 42a extends from the wall 38 to the cylinder 3. The lower end of the wall 29 and the forward ends of the walls 32 and 33 connect with the wall 42. A horizontal wall 43 extends from the upper edge of the wall 42 to the wall 10 and extends transversely of the construction inwardly from the lower end of the wall 30 and merges with the wall 23. There is thus provided by the walls 42 and 43, a forward inner portion of the wall 14 and a lower inner portion of the wall 10, a box-shaped portion defining a cored space 43a similar to the space 40a. The cored space 43a merges at its outer end with the cored space 28 and at its inner end with the cored space 21.

A substantially horizontal wall 44 connects the upper edge of the wall 42a with the wall 10. The wall 44 extends transversely of the construction, from the wall 31 to a location near the middle of and spaced slightly above the cylinder 3. The walls 42a and 10 are formed correspondingly to the walls 39a and 11 respectively, and extend

downwardly and are connected at their lower ends, so that the walls 42a and 44 and a lower portion of the wall 10 form a box-shaped portion defining a cored space 44a similar to the cored space 41a and with which cored space 44a the cored spaces 28 and 36b merge. The inner rear end portion of the wall 44 connects with the wall 33.

Holes 45 are provided in the wall 16, one opposite each of the inner ends of the cored spaces 36, 41a and 44a. Holes 46 are also provided in the top wall 9 opposite the upper ends of the cored spaces 24 and 28. Holes 47 are provided in the end walls 11 and 10 opposite the rear and front ends respectively of the cored spaces 36a and 36b. Holes 48 are provided in the wall 12 opposite the ends of the cored spaces 40a and 43a. These various holes permit the removal of core material from the portions of the cored spaces adjacent thereto during the manufacture of the construction.

It will be noted that the cored spaces are open at their connecting ends to provide communication therebetween, thereby providing intercommunication between all of the cored spaces.

It will also be noted that by the aforescribed arrangement the construction is reinforced by box-shaped portions extending transversely, longitudinally and vertically, thereby adding materially to the strength of the construction and adapting it to offer a relatively great amount of resistance to stresses and strains imposed in any direction and at all of the so called critical locations.

When the term "box-shaped" is employed in this description and in the appended claims it refers to the cross sections of the confining walls taken transversely of the respective cored spaces.

While there has been hereinbefore described an approved embodiment of the invention it will be understood that many and various changes and modifications in form, structure and arrangement of parts may be made without departing from the spirit of the invention and that all such changes and modifications as fall within the spirit of the present invention as defined in the appended claims are contemplated as a part of this invention.

The invention claimed and desired to be secured by Letters Patent is:

1. A construction comprising a cylinder; a half cylinder saddle part of box-like shape connected with said cylinder and including a bottom wall and an inner side wall extending longitudinally throughout the length of said box-like part; an exhaust passageway from the outer side to the inner side and upwardly through the top of said part; and a reinforcing angular web spaced from said exhaust passageway adjacent the juncture of said walls comprising a portion integrally formed with said side wall, spaced a relatively short distance from and extending substantially parallel to said bottom wall, and a second portion integrally formed with said bottom wall, spaced a relatively short distance from and extending substantially parallel to said side wall providing a box-shaped structure, the juncture between said two portions being parallel to the juncture between said two walls, said structure defining a cored space relatively small in cross section with in said part extending substantially the length of said walls and to a substantially equal extent on each side of the transverse center plane of said part.

2. A construction comprising a cylinder; and

- a cylinder saddle part including a depending wall at the bottom thereof spaced from the inner side of said cylinder and adapted for engagement with a locomotive side frame member, and a plurality of box-shaped portions at the bottom of said part extending between and connecting said wall and said side of said cylinder, one of said portions being disposed at each end of said part and another of said portions being disposed midway between said ends of said part, the last said portion being closed at its end adjacent said side of said cylinder and said end disposed portions being open to the atmosphere at their ends adjacent said side of said cylinder.
15. 3. An integral cylinder saddle construction comprising an end wall; an outer side wall; and a web adjacent the juncture of said walls providing a reinforcing box-shaped structure defining a vertical cored space extending along said juncture within said construction.
20. 4. An integral cylinder saddle construction comprising a wall running horizontally in a longitudinal direction; a vertical end wall; vertical side walls connected with said end wall and with said horizontally running wall; a web adjacent the juncture of said horizontal wall and one of said side walls; and a web adjacent the juncture of said end wall and one of said side walls, said webs providing reinforcing box-shaped structures defining respectively horizontal and vertical cored spaces extending along said respective junctures within said construction.
25. 5. An integral cylinder saddle construction comprising a horizontal bottom wall; a vertical side wall connected with said bottom wall; a vertical end wall connected with said bottom wall; a web adjacent the juncture of said bottom wall and said side wall; and a web adjacent the juncture of said bottom wall and said end wall, said webs providing reinforcing box-shaped structures defining respectively longitudinal horizontal and transverse horizontal cored spaces extending along said respective junctures within said construction.
30. 6. An integral cylinder saddle construction comprising top and bottom walls running horizontally in a longitudinal direction; vertical side walls connected with said top and bottom walls; vertical end walls connected with said top and bottom walls and said side walls; a web adjacent the juncture of one of said side walls and one of said horizontally running walls; a web adjacent the juncture of one of said end walls and one of said side walls; and a web adjacent the juncture of one of said end walls and one of said horizontally running walls, said webs providing reinforcing box-shaped structures defining respectively longitudinal horizontal, vertical and transverse horizontal cored spaces extending along said respective junctures within said construction.
35. 7. An integrally cast construction comprising a cylinder; and a cylinder saddle part including a horizontal bottom wall, a vertical depending wall spaced from the inner side of said cylinder and adapted for engagement with a locomotive side frame member, and a plurality of webs providing reinforcing box-shaped structures extending between said depending wall and said side of said cylinder and having their upper portions extending above said bottom wall.
40. 8. An integral cylinder saddle construction comprising top and bottom walls running horizontally in a longitudinal direction; a vertical end wall connected with said top and bottom walls;
- vertical side walls connected with said top and bottom walls and with said end wall; and webs providing a system of interconnecting reinforcing box-shaped structures defining respectively a cored space adjacent the juncture of said end wall and one of said side walls, a cored space adjacent the juncture of one of said side walls and one of said horizontally running walls, and a cored space adjacent the juncture of said end wall and said bottom wall, said spaces extending along said respective junctures within said construction.
45. 9. A cylinder saddle construction comprising a wall running horizontally in a longitudinal direction; vertical walls connected with each other and each connected with said horizontally running wall, said walls defining said construction, and angular webs, one adjacent the juncture of two of said defining walls, and another adjacent another juncture of two of said defining walls forming two reinforcing box-shaped structures providing two angularly disposed cored spaces extending along said junctures within said construction, said structures being connected together at one of their ends and said spaces communicating with each other at said connected ends.
50. 10. An integral cylinder saddle construction comprising four contiguous walls providing a hollow construction box-shaped in cross section; a fifth wall joining the edges of said four walls adjacent thereto; and webs adjacent the junctures of said fifth wall with said four walls providing a hollow, rectangular ring-shaped, reinforcing structure defining a continuous cored space along said junctures within said construction.
55. 11. An integral hollow box-shaped cylinder saddle construction comprising six walls defining said construction; and webs adjacent the edges of two adjacent walls, each of said webs being integrally joined with the two walls meeting at its respective said adjacent edge, the joining lines being spaced from said adjacent edge and running in the same direction therewith, providing two hollow, rectangular ring-shaped, reinforcing structures having a common side portion at the juncture between said two adjacent walls defining a continuous cored space along said junctures within said construction.
60. 12. A one-piece cast half cylinder saddle construction of box-like shape comprising a side wall extending vertically and longitudinally; a second wall connected with said side wall at an angle thereto; an exhaust passageway extending from the outer side to the inner side and upwardly through the top of said construction; and a reinforcing angular web spaced from said exhaust passageway adjacent the juncture of said walls comprising a portion integrally formed with said side wall, spaced a relatively short distance from and extending substantially parallel to said second wall, and a second portion integrally formed with said second wall, spaced a relatively short distance from and extending substantially parallel to said side wall providing a box-shaped structure, the juncture between said two portions being parallel to the juncture between said two walls, said structure defining a cored space relatively small in cross section within said construction extending substantially the length of said walls and to a substantially equal extent on each side of the common transverse center plane of said walls.
65. 13. An integral hollow box-shaped cylinder saddle construction comprising a reinforcing web

disposed at a corner of said construction having an edge integrally connected with one of the walls of said construction forming said corner in spaced relation with the two junctures of said wall with the two other walls of said construction forming said corner and having its opposite edge integrally connected with said two other walls in spaced relation to said junctures, defining an angular cored space extending along said two junctures.

14. A one-piece cast hollow box-shaped half cylinder saddle construction comprising an exhaust passageway extending from the outer side to the inner side and upwardly through the top of said construction; and a reinforcing web

spaced from said exhaust passageway adjacent the juncture between two walls of said construction, having its opposite edges integrally connected respectively to said two walls in spaced relation with and parallel to at relatively short distances from said juncture providing a reinforcing box-shaped structure defining a cored space relatively small in cross section within said construction extending along said juncture substantially throughout its length and to a substantial- 10
15 extent on each side of the common transverse center plane of said two walls, said structure being provided with an opening for the removal of core material.

JAMES G. BLUNT. 15
